UNITED STATES PATENT OFFICE.

WILLIAM W. ALEXANDER, OF KANSAS CITY, MISSOURI, ASSIGNOR TO THE GILL - ALEXANDER ELECTRIC MANUFACTURING COMPANY, OF SAME PLACE.

ELECTRIC CIRCUIT.

SPECIFICATION forming part of Letters Patent No. 540,620, dated June 11, 1895.

Application filed March 24, 1890. Serial No. 345,056. (No model.)

To all whom it may concern:

Be it known that I, WILLIAM W. ALEXANDER, a citizen of the United States, residing at Kansas City, in the county of Jackson, 5 State of Missouri, have invented certain new and useful Improvements in Electric Circuits, of which the following is a specification, reference being had therein to the accompanying drawings.

Upon a telegraph line having a series of local stations thereon, the local battery of each station is a constant source of expense, and consequently its strength or tension is generally reduced to nearly the lowest point 10 at which it will operate the receiving instrument or sounder, with comparatively no extra force to operate a second electro-magnet placed in circuit with the sounder. The above stated arrangement is rendered necessary by 15 the local circuit and relay system, now in common use.

The object of my improvement is to provide a new arrangement of circuits by which the local battery circuit is closed alternately 20 through the sounder electro-magnet and through a second electro-magnet so as to give to each of said electro-magnets, separately, the full force of the battery, and also to allow 25 the sounder or receiving instrument to be cut or switched in or out of the local circuit without interfering in any degree with the operation 30 of the sounder. I attain this object by the mechanism and arrangement of circuits illustrated in the accompanying drawings, in 35 which—

Figure 1 is a diagram illustrating a local station upon a telegraph-line provided with a relay and a circuit-controlling device, together with a sounder and a local battery, but 40 forms no part of my invention. Fig. 2 is also a diagram illustrating a local station upon a telegraph-line arranged in accordance with my invention, with a front and back contact relay, a local battery, and sounder, together 45 with an electric circuit-controlling apparatus.

In said drawings, L L' represent an ordinary line wire upon which there is a station provided with a key K and a relay R. The armature of this relay is adapted to make 50 front and back contacts. The front contact point F is connected through an ordinary

sounder S, and local battery, L B, to the relay R in the ordinary manner. The back contact point B is connected through a second electro-magnet E, and the local battery, L B, to 55 the armature of relay R, said electro-magnet E being arranged to control the circuit of the call bell C. If the main line is closed the local circuit will be closed through the sounder which will receive all the force of the battery. 60 Now if the main line is opened, the local circuit will be broken through the sounder and closed through the electro-magnet E, and it will then receive all the force of the battery until the line circuit is again closed. 65

In the arrangement shown in Fig. 2, a switch D is placed in the sounder operating circuit, by which the said sounder or receiving instrument can be switched in or out of the circuit. When the said switch D is closed the local-circ- 70

uit is substantially the same as above de-

scribed. If the main line is closed the circuit

will be closed through the sounder S which

will receive all the force of the battery L B;

but if the main line is opened the local cir- 75

cuit will be broken through the sounder and

closed through the electro-magnet E and it

will receive all the force of the battery until

the line circuit is again closed.

In the arrangement shown in Fig. 1, the 80 call bell C is operated by the armature of the electro-magnet E closing the call bell circuit.

In the arrangement shown in Fig. 2, the call bell circuit is operated by an intermediate automatic circuit controlling device of 85 which a diagram elevation is shown, the same consisting essentially of a toothed wheel C W, a pawl Z and a pawl Y pivoted to a bell crank arm W, said pawl being adapted to engage under certain conditions with said 90 toothed wheel, a pivoted lever L'' having pendent hooks and pawls, and a retardation wheel R W; but said controlling apparatus forms no part of this invention and is fully described in an application for patent filed 95 by me November 15, 1889.

Having now described my invention, I claim—

The combination of a relay provided with front and back contacts, its armature, a bat- 100

tery, a sounder, and a switch in the sounder circuit, with a signal controlling device hav-

ing a toothed wheel and pawls on a division of the battery circuit and operated by the back contact of the relay; in which construction the sounder and signal controlling device are operated by the same battery without interfering with each other, and a different or contrary action is produced by the line pulsations upon the said sounder from that

upon the signal controlling device substantially as described.

In testimony whereof I affix my signature in presence of two witnesses.

WILLIAM W. ALEXANDER.
